UNITED STATES PATENT OFFICE.

GEORGE P. WISDOM, OF CHICAGO, ILLINOIS, ASSIGNOR, BY MESNE ASSIGNMENTS, TO MARTIN C. SCHWAB, OF CHICAGO, ILLINOIS.

SPIRAL CONVEYER.

No. 891,514.

Specification of Letters Patent.

Patented June 23, 1908.

Application filed October 17, 1907. Serial No. 397,899.

To all whom it may concern:

Be it known that I, GEORGE P. WISDOM, a citizen of the United States, residing at Manhattan Building, Chicago, in the county of Cook and State of Illinois, have invented a new and useful Improvement in Spiral Conveyers, of which the following is a specification.

My invention relates to certain new and useful improvements in spiral conveyers and is fully described and explained in the specification and shown in the accompanying drawing, in which:

Figure 1 is an elevation of my improved conveyor, the electrical circuit being shown diagrammatically; Fig. 2 is a perspective view of one of the stations of the conveyor, a portion of the outer casing being broken away to show the interior construction; Fig. 3 is a horizontal section in the line 3 of Fig. 1; Fig. 4 is a horizontal section in the line 4 of Fig. 1; Fig. 5 is a top plan of the brake mechanism; Fig. 6 is a side elevation of the same.

Referring to the drawings A is a cylindrical outer casing of ordinary form and within that said casing is a spiral slide-way A¹ of sheet metal or the like the same being in general of the form commonly used in spiral conveyers. The slide-way of my conveyor, however, is made a variable pitch as illustrated in the drawing, the pitch of the spiral being much less above and at the level of the discharge doors than it is higher up.

That is to say, after passing any floor or opening where material may enter, the spiral has a very steep pitch until just before it reaches an opening where material can be ejected and at such point the pitch of the spiral is greatly decreased as illustrated. The purpose and mode of operation of this variable pitch spiral will presently be explained.

The conveyor herein illustrated, which is typical of my invention, is shown as applied to a building having four stories. These stories will in practice be ordinarily the upper floor used as a stock room from which goods are supplied to the various lower floors excepting the lowest of the series, two or more intermediate floors usually used as sales rooms (two intermediate floors being used in this case) and a lower floor (usually the basement) which is used as a shipping room. Under ordinary circumstances in stores (where spiral conveyers find their

greatest sphere of usefulness) the stock is distributed from the upper floor downward to the intermediate floors where it is sold and wrapped. The wrapped packages are sent from these floors to the basement. 60 There are certain circumstances, however, when it may be desirable to ship from one intermediate floor to another and means is provided for this purpose although the same can be dispensed with if desired. 65

It will be obvious that no special door arrangement will be necessary or desirable at the upper end of the chute, any kind of an opening through which goods can be placed upon the slide-way being quite sufficient at 70 this floor. In the drawings the slide-way is shown as running to the top of the chute which is left open to receive goods. Similarly at the lower floor no special arrangement is necessary, the only action that takes 75 place being the ejection of the packages. For this reason the outer tube of the conveyor is simply perforated at its lower end and a spiral slide terminates at said perforation so that the packages can pass outward. 80 At the intermediate floors, however, some special arrangement is obviously necessary to afford means for the ingress and egress of packages and such means must be sufficiently under control from stories above the 85 stories at which they are located to permit goods at will to be sent through said openings or past them.

Outlet doors B are provided at the various stories as illustrated the same being slightly 90 above the level of the floors and connected to discharge slides down which the packages passing from said doors can slide. The said discharge doors B are movable vertically in suitable guides provided to receive them on 95 the tubular casing A, the construction of the said guides being clearly illustrated in the sectional view (Fig. 3). It will be seen that these doors are so arranged that they lie flush with the inner face of the tube so that no 100 shoulder is formed against which the packages can strike in passing, so as to be damaged thereby. At the lower lateral edge of each discharge door B is located a radially disposed vertically movable stop-plate C. 105 The stop-plates C are guided between channel guides mounted in the outer casing A and in a central strengthening post running along the inner edge of the slide-way A¹. The discharge doors and the corresponding stop- 110

plates are for convenience made of substantially the same size and weight so that one may serve as a counter-balance for the other and the same are connected by ropes or 5 cables c which pass up from the discharge doors B over guide sheaves c^1, c^2 and over and around a drum c^3 downward to the said stop-plates. The drums c^3 are mounted upon radially disposed shafts c^4 , mounted as illustrated in Fig. 4. It will thus be evident that 10 by rotating the shafts c^4 it will be possible to raise the discharge doors and lower the corresponding stop-plates, and that these motions can be accomplished without the expenditure of great force as the two parts substantially counter-balance each other. The 15 rope connecting the stop-plate and discharge door is so arranged that when the door is closed the stop-plate will be raised a sufficient distance above the slide-way to permit the passage of the largest articles which the chute will accommodate beneath it. When the discharge door is raised the stop-plate will be lowered into the path of articles moving 20 along the slide-way so that any article which passes down the slide-way will be arrested by the stop-plate and by it deflected toward the opening covered by the discharge door. Intake doors D through which articles 25 can be inserted into the conveyer, are provided below the discharge doors at each story, and these doors are so disposed above the plane of the slide-way at the points at which they are situated as to make it impossible 30 for packages to pass outward through the intake doors.

In order to provide means by which the various discharge doors can be opened from the various floors above them respectively, 40 each of the shafts c^4 is provided at its outer end with a sheave e about which run ropes E, E^1 which extend in loops above the end of the conveyer and are supported by sheaves e^1, e^2 . By manipulating the rope E the 45 lower of the two intermediate doors can be operated from either of the floors above it and by manipulating the rope E^1 the upper of the two intermediate doors can be operated from the upper floor of the building. 50 It is obviously desirable to provide means whereby the fact that any discharge door is open will be indicated to the floors above said discharge door in order that packages may not inadvertently be sent to the wrong 55 floor.

It will be understood that normally the chute is in such condition that packages deposited in it will reach the shipping room in the basement and in the absence of some 60 variable signal any person using the chute will naturally presume that it is so set. Should the chute, however, be set to discharge say at the lower intermediate floor this fact should be plainly indicated at the 65 floors above although such indication is not

necessary at the lower intermediate floor and should the chute be set to discharge at the upper intermediate floor this fact should be indicated at the upper floor but not necessarily at the lower intermediate floor or at the 70 upper intermediate floor where the door is open for from both these floors goods can be transmitted to the shipping-room in the ordinary way. In order to provide this indicating or signaling system the sheaves 75 e^1, e^2 are mounted upon shafts F, F^1 (Figs. 5 and 6) journaled somewhat loosely at one end so as to be capable of limited horizontal oscillation. The opposite ends of the shafts are supported in eccentric sleeves 80 G, G^1 , respectively, said sleeves bearing radially projecting arms g, g' , by which they can be rotated. The shafts have fixed upon them friction disks H, H^1 which can be brought into enjoinder with fixed 85 brake shoes h, h' by horizontal oscillation of the shafts F, F^1 . When either radial arm is lowered the corresponding sleeve will be so turned as to swing the friction disk of the corresponding shaft against the shoe and 90 when it is raised the shaft will be swung away to a released position.

Solenoids I, I^1 are provided by which these radially projecting arms may be operated, the solenoid I being arranged to release the 95 brake to permit the rope E to be manipulated, the solenoid I^1 being arranged to permit the manipulating of the rope E^1 . These solenoids are arranged in circuits J, J^1 which are illustrated diagrammatically in Fig. 1. A 100 trunk circuit or line K is provided and switches J are arranged at the upper and upper intermediate floors whereby current from the supply circuit K can be admitted to the circuit J and a switch j^1 is similarly provided at the 105 upper floor for admitting current to the circuit J^1 . In addition to the solenoids the circuit J and J^1 includes lamps and buzzers or other audible signals j^2, j^3 . The said signal j^2 being arranged at the upper and upper intermediate floors and the signal j^3 at the upper floor only. Thus it will be seen that under ordinary conditions the discharge doors 110 cannot be operated. When it is desired to open one of the said discharge doors for the 115 purpose of ejecting packages at any floor above the basement, the operator at any higher floor closes the switch in the corresponding circuit. This releases the rope controlling said door and simultaneously turns 120 on the light and sounds the audible signal at each floor above the floor where the door to be operated is located. The operator can then and only then operate the discharge door and the continued sounding of the signal 125 will remind him to return the door to its original position as soon as he has finished using the chute. The presence of the light and the sounding of the audible signal will be a warning to operators at other floors that the chute 130

is set to discharge at a floor other than the lowest and will also indicate at which floor it is set to discharge.

I realize that considerable variation is possible in the details of the construction herein set forth. This is particularly true of the electrical circuit and brake mechanism, for these are capable of almost endless variation without departing from the spirit of my invention.

It will be noticed that the construction herein described provides a chute having all the desired capacities of operation in that it can be set to discharge at any desired floor and when so set will warn those located at floors above not only that it is set to discharge at a lower floor but at which floor it is set to discharge. Furthermore the means by which the conveyer is arranged to discharge at intermediate floors is particularly desirable and effective. The effectiveness of this arrangement is enhanced by the fact that the pitch of the spiral slide-way is decreased at the points of exit. A package moving down the chute at high velocity is checked in its descent just before it reaches any discharge door, but its inertia keeps it in motion so that it is thrown with considerable force against the outer wall of the conveyer. In this way its progress is still further arrested and it is given an outward or centrifugal tendency which causes it readily to leave the chute through the discharge door when opened. Thus the shock which the package sustains in bringing up against the stop-plate is minimized and it may even be possible to dispense with the stop-plate altogether with this arrangement, the stop-plate being intended largely as a precaution to prevent the package from passing the door. By arranging the stop-plates and discharge doors so that each acts as a counter-balance for the other the amount of force required to operate the doors is greatly decreased and by arranging the operating rope or cable double as illustrated no counter-balance for the rope is necessary so that all the force necessary is simply that required to overcome the inertia and friction of the parts.

I realize that considerable variation is possible in the details of construction of my improved device, without departing from the spirit of my invention and I do not intend therefore to limit myself to the specific form herein shown and described.

What I claim as new and desire to secure by Letters Patent is—

1. A device of the class described having an outer casing and a discharge door therein and a spiral slide-way within the outer casing having a decreased pitch as it approaches said discharge door.

2. In a device of the class described the combination with an outer casing and a movable discharge door therein of a spiral slide-

way having a decreased pitch as it approaches such discharge door.

3. The combination with an outer casing having a discharge door therein and a spiral slide-way having a decreased pitch as it approaches 70 said discharge door of means of controlling the door from a floor above the floor at which it is located.

4. The combination with an outer casing having a discharge door therein and a spiral 75 slide-way within the casing having a decreased pitch as it approaches the discharge door; of a movable stop located at the lower lateral edge of the discharge door and means for interposing the stop in the path of articles 80 upon the slide-way.

5. The combination with an outer casing having a discharge door; of a slide-way therein having a decreased pitch as it approaches 85 the discharge door; a stop adapted to be interposed in the path of articles upon the slide-way, a means for opening the discharge door and simultaneously interposing the stop in the path of said articles.

6. The combination with an outer casing 90 having a discharge door therein and a slide-way having decreased pitch as it approaches the discharge door; of a vertically movable stop at the lower lateral edge of said discharge door and means controllable from a 95 floor above the discharge door for simultaneously opening the door and interposing the stop in the path of articles upon the slide-way.

7. The combination with an outer casing 100 having a discharge door therein; of a spiral slide-way within the casing; a stop-plate vertically movable at the lower lateral edge of the discharge door and means for simultaneously moving said discharge door and stop 105 in opposite directions.

8. The combination with an outer casing of a spiral slide-way therein and a discharge door in said outer casing of a stop at the lower lateral edge of said discharge and 110 means for lowering said stop and simultaneously raising said door.

9. The combination with an outer casing having a discharge opening controlled by a discharge door and a spiral slide within the 115 casing; of a stop arranged at the lower lateral edge of said door and vertically movable and means of connection between said discharge door and stop whereby the same can be oppositely moved and whereby the same 120 counter-balance each other.

10. The combination with an outer casing having a discharge door; of a spiral slide-way within the casing and means for controlling the door from floors above it and a signaling 125 device located at the floors above the discharge door and arranged to indicate the position of said discharge door.

11. The combination with an outer casing having a discharge door; of a spiral slide-way 130

- therein, a device for normally preventing the operation of said discharge door, means for releasing the said discharge door to prevent its operation, and a signaling device at the 5 floors above the discharge door arranged to be operated with said releasing means.
12. The combination with an outer casing having a discharge door therein and a spiral slide-way within the casing; of means for 10 normally preventing the operation of the discharge door, electrically controlled means for releasing said device to permit the operation of the discharge door and signaling means in the electric circuit thereof to indicate the position of the discharge door.
13. In a device of the class described the combination with an outer casing having an opening and a slide-way within the casing; of a discharge door controlling the opening, a 15 radially arranged vertically movable stop-plate at the lower lateral edge of the opening, a rope connecting the discharge door and stop-plate whereby they counterbalance

each other and are oppositely moved simultaneously and means controllable from a 25 floor above the opening for operating the door and stop-plate.

14. The combination with an outer casing of a discharge opening and a spiral slide-way within the casing; of a discharge door controlling the opening, a guided stop-plate vertically movable at the lower lateral edge of the opening, a shaft having a drum thereon, a rope connecting the discharge door and said stop-plate and passing over the drum 35 upon said shaft whereby the door and stop-plate counterbalance each other and are both movable by rotation of the shaft and means controllable from the floor above said discharge door for rotating said shaft to 40 move the door and stop-plate.

GEORGE P. WISDOM.

In presence of—
A. U. THORIEN,
R. A. SCHAEFER.
